CLAIM

The ornamental design for a finned heat exchanger plate, as shown and described.

DESCRIPTION

FIG. 1 is a top plan view of a finned heat exchanger plate showing my new design;

FIG. 2 is a side elevational view thereof as seen from the right side in FIG. 1, the opposite side being a mirror image;

FIG. 3 is a side elevational view thereof as seen from the bottom of FIG. 1, the opposite side being a mirror image;

FIG. 4 is an enlarged sectional view thereof as seen along line 4—4 in FIG. 1;

FIG. 5 is a bottom plan view thereof.

FIG. 1

FIG. 2

FIG. 3

FIG. 4

FIG. 5
